UNITED STATES PATENT OFFICE.

SAMUEL G. EDMONDSON, OF ST. LOUIS, MISSOURI.

DESIGN FOR A LAMP STANDARD.

Application filed April 20, 1928. Serial No. 26,398. Term of patent 7 years.

To all whom it may concern:

Be it known that I, SAMUEL G. EDMONDSON, a citizen of the United States of America, residing in the city of St. Louis, in the State of Missouri, have invented a new, original, and ornamental Design for Lamp Standards, of which the following is a specification, reference being had to the accompanying drawing, forming a part thereof.

Figure 1 is a front elevation of a lamp standard embodying my new design.

Figure 2 is a side elevation of a lamp standard embodying my new design.

I claim:

The ornamental design for a lamp standard, as shown.

SAMUEL G. EDMONDSON.
